ATTORNEY

UNITED STATES PATENT OFFICE.

ARTHUR SHERIDAN HUGHES, OF MANSFIELD, OHIO.

INTERLOCKED-STEP CONSTRUCTION.

Application filed April 21, 1922. Serial No. 555,908.

To all whom it may concern:

Be it known that I, ARTHUR S. HUGHES, a citizen of the United States, residing at Mansfield, in the county of Richland and State of Ohio, have invented new and useful Improvements in Interlocked-Step Constructions (Case B), of which the following is a specification.

This invention relates to stair construction, particularly to that type in which the steps consist of metallic risers and thread members, the latter being covered or filled with plastic material; and has for its object the provision of novel means for interlocking the treads and risers so as to provide a rigid structure, in which the parts cannot become separated or displaced.

An important and more specific object is the provision of a structure of this character in which the risers and tread members are formed with flanges between which are disposed elements which have the combined functions of braces, spacers and locks.

The construction, arrangement and utility of the structure will be readily comprehended from a study of the description taken in conjunction with the accompanying drawings, though it is to be distinctly understood that the detailed disclosure is merely the exemplification of a number of preferred embodiments of the invention, and that I reserve the right to adopt many variations and make such modifications as will widen the field of its usefulness, provided always that such changes involve no departure from the salient features of the invention, or the scope of the appended claims.

In the drawings:

Figure 1 is a vertical sectional view through a step constructed in accordance with one form of my invention;

Figure 2 is a vertical section on the line 2-2 of Figure 1;

Figure 3 is a horizontal section on the line 3-3 of Figure 1;

Figure 4 is a cross section disclosing a second form;

Figure 5 is a cross section through a third form;

Figure 6 is a similar view showing a 50 fourth modification;

Figure 7 is a section showing a fifth modification;

Figure 8 is a similar view illustrating a 55 sixth modification;

Figure 9 is a cross section through a seventh form;

Figure 10 is a similar view showing an eighth modification;

Figure 11 is a section through a ninth 60 form;

Figure 12 is a detail perspective view of the lock or brace used in the last-disclosed form.

Referring more particularly to the drawings, the letter A designates a tread member, B designates a riser, while C designates the usual horizontally disposed bolt or stay rod which is commonly provided in stair construction of this type at the juncture of 70 the tread member with the riser. The tread member and riser are formed in one piece, as disclosed in my companion application No. 555,907. It is not thought necessary to show this in the present application. 75

In Figures 1 to 3 inclusive, I have shown the tread member as formed, forwardly of the stay rod, with a forwardly and downwardly inclined bottom wall or portion 10, 80 at the end of which is formed a vertical wall or flange 11. The riser is formed at its upper end with a corresponding and contacting inclined portion or shelf 12 and vertical flange or wall 13, which conforms to engage against the inclined bottom wall or portion 10 and flange or wall 11, respectively. Formed integrally at the upper edge of the vertical wall or flange 13 is a nose piece 14 which is pressed or otherwise formed to define a longitudinal channel 15, within which is held a strip or block 16 of non-slipping material which projects above the top of the nose piece. Instead of a channel

and a strip or block of material, a series of spaced sockets with material in each socket may be employed, as disclosed in my aforementioned companion application. The wall or flange 13 is spaced from and cooperates with the adjacent side of the channel portion 15 to define a recess or pocket into which fits the upper edge of the vertical wall or flange 11.

10 The letter D designates plastic material which rests upon and in actual practice is molded upon the tread member A and has its top surface flush with the top face of the nose piece 14. The latter is partially bedded in the plastic material.

15 While the above described parts constitute an interlocking connection for the tread member and riser, I find it advisable to provide spacing and bracing means, which in the present instance is illustrated as consisting of short sections 17 of channel iron or the like, which are arranged at spaced intervals throughout the width of the step, and have their lower ends inclined to rest 20 upon the inclined portion 10 of the tread member and their upper ends engaging against the underside of the channel portion.

25 In Figure 4 I have shown the nose piece 18 as being plain, that is, not provided with the nonslippping strip holding channel above described, the nose piece being, however, formed at its free edge with a depending flange 19. The tread member is formed at its front edge with an upwardly extending flange 20, which is not as high as the corresponding flanges 11 of the first-described form. However, I make use of exactly the same spacing members 17 as in Figures 1, 2 and 3 which are positioned 30 and which function in the same way.

35 In Figure 5 the construction is exactly the same as in Figure 4, except that the forward portion of the tread member is straight or horizontal instead of inclined, as shown 40 in Figures 1 and 4.

45 In Figure 6 the construction is the same as in Figure 5, except that instead of the spacing members 17, I provide spacing members 21 which are of acute angular 50 shape, that is, similar in shape to the numeral 7, there being a horizontal leg 22 which bears against the underside of the nose piece, and an inclined body portion which extends diagonally from the angle formed by the flange 19 of the nose piece 55 to the angle formed by the flange 20 extending from the tread member.

60 In Figure 7 the tread member and riser are shown as having contacting inclined portions 10, 12 at the front edge, as in Figures 1 and 4, though the nose piece is of exactly the same formation as in Figures 4, 5 and 6. The locking means in this 65 instance consists of any number of spaced inverted L-shape members 23, which have

their lower edges engaging in the angle at the juncture of the flange 20 with the inclined bottom portion 10 of the tread and have their upper or horizontal portions 24 disposed against the underside of the nose 70 piece.

75 In Figure 8 the nose piece is shown as being of substantially the same construction as in Figure 1, the only difference being that the nose piece is formed with a depending flange 25, which cooperates with the adjacent side of the channel portion 15^a to define a pocket, within which is engaged the upper ends of angularly shaped braces 26, which are inclined, as shown, and have 80 their lower ends engaged in the angle at the juncture of the flange 20 with the tread member. In this form it is likewise to be observed that the contacting portions of the tread member and riser are horizontal, as 85 in Figures 5 and 6, though they may be inclined as in Figures 1, 4 and 7, if desired.

90 Figure 9 shows another variation over Figure 8. This particular modification shows the nose piece as having a non-slippping strip receiving channel 15^b, having its bottom inclined downwardly and rearwardly with respect to the front edge of the step. The locking and supporting means in this instance consists of a series of angular 95 members 28, which have their lower ends engaged in the angle formed by the juncture of the flange 20 with the body of the tread member and have their upper flanges 29 engaging against the bottom of the channel. 100

105 Figure 10 shows a form which varies from Figure 1 in the utilization of a different type of spacing and locking means, which is shown as consisting of a plurality of angularly shaped supports or members 30, which have their lower ends engaging in the angle of the flange 20, and have their upper flanges 31 bearing flat against the underside of the channel member 15^c, with the free edges of these 110 flanges 31 formed with vertical flanges 32 fitting within the pocket defined between the vertical wall portion 13 at the forward edge of the step and the adjacent side of the channel member. 115

120 Figure 11 differs from Figure 10 in illustrating another form of bracing and locking means, which consists of a series of members, each of which includes plate portions 33 and 34 arranged at right angles to each other, with the end of one projecting beyond the end of the other. The plate portion 33 has its lower end engaging upon the bottom wall or portion 10 of the tread member, and its upper end engaging against 125 the underside of the channel member 15^a, while the plate member 34 has its lower end engaging upon the top of the flange 20, and its upper end received within the 130 pocket defined between the vertical portion 130

13 at the front of the step and the adjacent side of the channel member.

In all the forms of the device it will be seen that regardless of whether the nose piece be formed to retain a strip of non-slipping material, or whether it be formed plain, I have provided ample means for bracing and interlocking the nose piece with respect to the lower portion of the step; 10 that is to say, with respect to the contacting portions of the tread and the riser, so that there will be no tendency toward collapsing. It is to be noted that the various shapes of the supporting and locking members will take care of all modifications in the specific construction of the nose piece. 15 As the locking elements are themselves embedded within the plastic material which forms the tread proper, it is apparent that there is no possibility of their becoming displaced even after prolonged use, and it is consequently obvious that the structure should have the maximum degree of strength in addition to its other manifest advantage 20 of simplicity.

I have shown the locking elements in separate pieces. They could be made in one piece, if desired, so as to extend the full width of the step.

30 The nose piece being formed integral with the vertical wall or flange of the riser may be regarded as a flanged continuation of the latter.

Some of the claims of this application 35 are generic to the construction shown in my companion application No. 555,909.

What is claimed is:—

1. In a stair construction, a step including a riser and a tread member, both formed of sheet metal with interfitting vertical flanges at the front edge of the step forming the nose thereof, and locking means interposed between the tread and riser and engaging said flanges.

45 2. In a stair construction, a step including a riser and a tread member, both formed of sheet metal with interfitting vertical flanges at their front edges, the riser having a horizontal flange at the top of the vertical flange, and locking means interposed between the tread and riser and engaging said horizontal flange of the riser and the tread member, said locking means being formed of 50 separate elements arranged at intervals.

55 3. In a stair construction, a step including a riser and a tread member, both formed of sheet metal, a nose piece extending inwardly over the tread member from the riser, and spaced from the tread member, and combined spacing, bracing and locking means 60 engaging said nose piece and said tread member.

4. In a stair construction, a step including 65 a riser and a tread member, both formed of sheet metal with interfitting vertical flanges,

a nose piece formed by an integral continuation of the vertical flange of the riser and covering the front edge of the step and spaced from the tread member, and bracing and spacing means disposed between and 70 engaging the nose piece and tread member.

5. In a stair construction, a step including a riser and a tread member both formed of sheet metal with interfitting vertical flanges at the front edge of the step, a nose 75 piece formed integrally with the vertical flange of the riser and extending inwardly from the front edge of the step, and bracing and spacing means disposed between the nose piece and tread member, and engaging said flanges whereby to constitute locking means.

6. In a stair construction, a step including a riser, a tread member both formed of sheet metal with interfitting flanges at the nose 80 of the step, a nose piece formed upon the riser and overlying the tread member, and combined locking and bracing means engaged between the tread member and nose piece and located wholly at the nose of the 85 step.

7. In a stair construction, a step including a tread member of sheet metal formed at its front edge with an upstanding flange, a riser of sheet metal formed with a vertical portion disposed against said flange and forming the front edge or nose of the step, the vertical portion of the riser being continued inwardly to form a nose piece overlying but spaced from the tread member, and bracing means disposed between the 90 tread member and nose piece.

8. In a stair construction, a tread member having its bottom wall inclined downwardly and a vertical flange extending upwardly 95 from its front edge, a riser having at its upper end an inclined shelf to receive the inclined bottom wall of the tread member, a vertical wall extending upwardly from the riser and constituting the front wall of the 100 step, and an inturned flange provided on the upper end of the vertical wall, said inturned flange having its upper face substantially flush with the top of the tread surface of the tread member.

115 9. In a stair construction, a tread member having an upstanding flange at its front edge, and plastic material provided on said tread member and constituting the tread surface of the step, a riser having its upper end formed with a shelf to receive the front portion of the tread member, a vertical flange extending from the outer end of the shelf, and an inturned flange at the upper edge of the vertical flange, the flanges of 120 the tread member and riser interfitting, said inturned flange constituting a nose piece.

125 10. In a stair construction, a tread member provided at its front edge with an up-

- standing flange and having plastic material supported thereon and constituting the tread surface of the step, a riser having at its upper end a shelf supporting the front end of the tread member, a vertical flange extending upwardly from the shelf and forming the front face of the step, and an inturned flange extending from the vertical flange and partially embedded in the plastic material of the step, said inturned flange forming a nose piece.
11. In a stair construction, the tread member having at its front end an upstanding flange and provided with plastic material thereon constituting the tread surface of the step, a riser having at its upper end a shelf supporting the front edge of the tread member, a vertical wall extending upwardly from the shelf and forming the front face of the step; and an inturned flange extending from the vertical wall and forming a nose piece for the step, said inturned flange being pivotally embedded in the plastic material and having a recess to receive a filling of non-slipping material.
12. In a stair construction, a step including a riser and a tread member, both formed with interfitting flanges, and a nose piece formed integral with the riser and having a depending channel forming portion to receive non-slipping material.
13. In a stair construction, a step including a riser and a tread member both formed with interfitting flanges, and a nose piece formed integral with the riser and having a depending channel forming portion to receive non-slipping material, and a bracing means interposed between the channel forming portion and the tread member.
14. In a stair construction, a tread member and a riser formed with interfitting flanges, a nose piece formed integral with the riser, plastic material supported on the tread member and in which the nose piece is partially embedded, and a bracing means interposed between the nose piece and the tread member and also embedded in the plastic material.
15. In a stair construction, a tread member and a riser having interfitting flanges, a nose piece formed integral with the riser, and a nose piece formed integral with the riser, plastic material upon the tread member, said nose piece having a depending channel, and a bracing means interposed between the channel and the tread member and imbedded in the plastic material.
16. In a stair construction, a tread member formed at its front edge with an upstanding flange, a riser having its upper end formed with a shelf to receive the front edge of the tread member, a vertical flange extending upwardly from the shelf and bearing against the flange of the tread member, and forming the front face of the step.
17. In a stair construction, a tread member forming at its front edge with an upstanding flange; a riser having its upper end formed with a shelf to receive the front edge of the tread member, a vertical flange extending upwardly from the shelf and bearing against the flange of the tread member, and forming the front face of the step, and bracing means interposed between the nose piece and the tread member.
18. In a stair construction, a tread member having at its front edge a vertical flange, a riser having at its upper end a shelf to receive the front edge of the tread member, a vertical wall extending upwardly from the shelf, and an inturned flange at the upper end of the vertical wall, said inturned flange having a depending socket to receive non-slipping material, plastic material resting upon the tread member and having its upper surface substantially flush with the upper face of said flange, and a bracing means engaging the socket and the bottom wall of the tread member.
19. In a stair construction, a tread member having its front edge formed with a vertical flange, a riser having its upper end formed with a shelf to receive the front edge of the tread member, a vertical wall extending upwardly from the shelf, and an inturned flange provided at the upper end of the vertical wall, said upturned flange constituting a nose piece, plastic material placed upon the tread member and having its upper surface substantially flush with the upper face of said nose piece, and bracing means interposed between the underside of the nose piece and the front edge of the tread member, said bracing means engaging with the front flange of said tread member and embedded in the plastic material.
20. In a stair construction, a tread member formed with a plastic tread face, a nose piece having a depending channel embedded in said face, and a filling of non-slipping material in said channel.
21. In a stair construction, a tread member having its front edge formed with a

vertical flange, a riser having its upper end formed with a shelf to receive the front edge of the tread member, a vertical wall extending upwardly from the shelf, said vertical wall fitting against the vertical flange of the tread member, and a nose piece having a depending channel spaced from the verti-

cal wall of the riser to form a pocket to receive the vertical flange of the tread member and become interlocked therewith. 10

In testimony that I claim the foregoing as my own, I have hereto affixed my signature.

ARTHUR SHERIDAN HUGHES.
